UNITED STATES PATENT OFFICE.

SAMUEL FRENCH, OF BOSTON, ASSIGNOR TO HIMSELF, AND SIDNEY ALLEN,
OF NEWTON, MASSACHUSETTS.

IMPROVEMENT IN SAFETY-POCKETS.

Specification forming part of Letters Patent No. 35,731, dated June 24, 1862.

To all whom it may concern:

Be it known that I, SAMUEL FRENCH, a citizen of the United States of America, and a resident of Boston, in the county of Suffolk and State of Massachusetts, have invented a new and useful or Improved Safety-Pocket for Wearing-Apparel; and I do hereby declare the same to be fully described in the following specification, and represented in the accompanying drawings, of which—

Figure 1 exhibits it in side elevation; Fig. 2, in transverse section. Fig. 3 is a section taken longitudinally through the flexible arm and bolt-actuator.

The nature of my invention consists in the combination of a flexible arm and bolt-actuator with a pocket and its fastening apparatus, the whole being substantially as hereinafter explained.

In making my said invention I have sought to produce a safety bag or pocket not only provided with a lock or fastening apparatus, but with devices which, while the pocket may be applied to the dress of a person, shall extend to a distant part of the body or dress of the wearer of the pocket a means of unlocking the mouth of the pocket. The object of these last-named devices is to prevent the pocket from being picked or opened by any other person than the wearer. Persons who are in the habit of traveling in street-railway carriages or omnibuses are liable to have their pockets rifled or picked; but with my improved pocket it will be difficult, if not impossible, for such to occur.

In the drawings, A exhibits a bag or pocket, which may be constructed either in whole or in part of chain-work or metal wires woven or interlaid together. The jaws *a b* of the mouth of the pocket I provide with a locking

apparatus, which consists of a spring-bolt, *c*, and a catch, *d*, applied, respectively, to the jaws. By pressing the said catch inward the bolt will be forced backward until the notch *e* of the catch may be in a position to permit the spring *f* of the bolt to advance the bolt or shoot it forward into the notch.

From the inner jaw I extend a thin flexible spring or bar of steel, *g*, alongside of which I place what I term the "bolt-actuator" *h*. This latter consists of a thin flexible spring or bar of metal, which is provided with a knob or button, *i*, whose shank goes through a slot, *k*, formed on the flexible bar *g*.

If, now, we suppose the pocket with the bar *g* to be fastened to the dress of a person and in a position which will hang the pocket over or near to the upper part of one leg of the individual, the flexible bar or arm *g* will extend across the abdomen or up to and partially around the waist. After the pocket under such circumstances may have been closed the means of unlocking it will be situated at the waist of the wearer, and if such is known only to him or her, as the case may be, it would be very difficult, if not impossible, for a robber to pick the pocket or obtain access to its contents. The flexible arm and bolt-actuator will bend with and conform themselves to the body of the person while the pocket may be in use.

I claim—

The combination of the flexible arm and bolt-actuator or their equivalent or equivalents with the pocket and its fastening apparatus, the whole being substantially as specified.

SAMUEL FRENCH.
